UNITED STATES PATENT OFFICE.

GEORGE R. JARMAN, OF BALTIMORE, MARYLAND, ASSIGNOR OF ONE-FOURTH TO
W. A. MATTHEWS, ONE-FOURTH TO L. A. MATTHEWS, AND ONE-FOURTH TO T. R.
MATTHEWS, ALL OF BALTIMORE, MARYLAND.

DEVICE FOR SUPPLYING STEAM AND AIR TO FURNACES.

1,186,201.

Specification of Letters Patent.

Patented June 6, 1916.

Application filed February 23, 1915. Serial No. 10,008.

To all whom it may concern:

Be it known that I, GEORGE R. JARMAN, a citizen of the United States of America, and resident of Baltimore, in the State of Maryland, have invented certain new and useful Improvements in Devices for Supplying Steam and Air to Furnaces, of which the following is a specification.

This invention relates to devices for feeding steam and air to furnaces for the purpose of supporting combustion and insuring consumption of fuel so as to acquire the maximum efficiency for a given quantity of fuel.

An object of the present invention is to provide novel means for utilizing jets of steam so directed with respect to an air intake that a partial vacuum is created within the air intake and the said partial vacuum results in drawing increased volumes of air through the air intake so that it will be delivered under the grate bars and find its way therethrough to the fire bed.

A further object of this invention is to produce a steam supplying medium so made as to deliver the steam to the air delivery pipe so that it will have a whirling action and the force thereof will be equal practically throughout the diameter of the air intake, thereby causing the current of air in the said air intake to be uniform throughout its cross sectional area.

A still further object of this invention is to produce a steam supplying medium requiring a comparatively small volume of steam for moving a given volume of air in the air intake, this due to the fact that the said steam is delivered in relatively small jets and tangentially to the axis of the air intake.

With the foregoing and other objects in view, the invention consists in the details of construction and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a view in elevation of a furnace, the same being broken away to show the invention applied thereto; Fig. 2 illustrates an enlarged detail sectional view 55 of an air intake and the invention applied thereto.

In these drawings 10 denotes the wall or casing of a furnace with a steam and air feeding device 11 applied to each side thereof, it being shown that the said air and steam feeding device is applied to the side wall of one section and to the front door of the ash pit of the other section.

In carrying out the invention, I utilize an 65 air supply pipe 12 with a flared outer end 13, the said outer end being guarded by a damper 14 so that openings through the outer end may be restricted or increased according to the volume of air which is necessary for producing the intended results.

A steam supply pipe 15 leads through a bushing 16 on the flared portion of the intake pipe and through an aperture 17 in said flared portion, the said steam supply pipe 75 having an extension 18 lying axially of the air supply pipe. The inner end of the extension 18 has a head 19 apertured and threaded to receive the nipples 20 of the jets.

I claim—

In a device for feeding steam and air to furnaces, an air supply pipe having a flared extremity and a restricted portion, means for controlling the volume of air into said air supply pipe, a steam supply pipe having 85 an extension lying axially of the air supply pipe and terminating at a point within the restricted portion thereof, a removable circular head having a convexed portion positioned on one end of said steam supply pipe, 90 said convexed portion of the head having a plurality of openings disposed at an angle with relation to the extension of the steam supply pipe, and removable nozzles positioned in the respective openings of the convexed portion of said head.

In testimony whereof, I hereunto affix my signature in the presence of two witnesses.

GEORGE R. JARMAN.
